The ornamental design for a ratchet clamp, as shown and described.

DESCRIPTION

FIG. 1 is a perspective view of a ratchet clamp of the present invention;

FIG. 2 is a plan view of the left side of the ratchet clamp of FIG. 1 with the right side being a mirror image;

FIG. 3 is an end view of the closed jaws of the ratchet clamp of FIG. 1; and

FIG. 4 is a plan view of the bottom of the ratchet clamp of FIG. 1.

FIG. 5 is a perspective view of an embodiment of a ratchet clamp of the present invention in an open position;

FIG. 6 is an elevational view of the left side of the ratchet clamp of FIG. 5 with the right side being a mirror image;

FIG. 7 is an end view of the open jaws of the ratchet clamp of FIG. 5;

FIG. 8 is a plan view of a top of the ratchet clamp of FIG. 5 with the bottom view being a mirror image; and,

FIG. 9 is an elevational view of the left side of the ratchet clamp of FIG. 5 with the clamp in a closed position.
